UNITED STATES PATENT OFFICE

116,736

DESIGN FOR A PAPER ROLL HOLDER

Elvah O. Bulman, Grand Rapids, Mich.

Application February 13, 1939, Serial No. 82,945

Term of patent 14 years

To all whom it may concern:

Be it known that I, Elvah O. Bulman, a citizen of the United States, residing at the city of Grand Rapids, in the county of Kent and State of Michigan, have invented a new, original, and ornamental Design for a Paper Roll Holder, of which the following is a specification, reference being had to the accompanying drawing, forming a part thereof.

The figure is a perspective view of a paper roll holder showing my new design.

I claim:

The ornamental design for a paper roll holder, as shown.

ELVAH O. BULMAN,
